LIQUID DIVIDING AND DISPENSING
SYSTEM

Edwin J. Hull, Cleveland, Ohio, assignor to
Trabon Engineering Corporation, Cleveland,
Ohio, a corporation of Ohio

Application November 20, 1939, Serial No. 305,229

14 Claims. (Cl. 184—7)

The present invention pertains to liquid dividing and dispensing systems and devices.

When dispensing oil and particularly when dispensing grease through reversible circuitous dispensing systems, it has been found that it is better practice to make short dispensing circuits, as the longer the circuit, the greater is the possibility of trouble arising, due to friction and/or compression of air in the grease, and/or other causes. To make a number of small flow-reversing systems heretofore required a plurality of pumps and a plurality of flow-reversing valves which made the systems very expensive.

Therefore, it is an object of this invention to provide a liquid dividing and dispensing system comprising a liquid divider including a plurality of circuits, each circuit having or being adapted to have a reversible fluid dispensing valve or valves or feeder or feeders connected thereto, said system requiring but one pump or source for delivering liquid thereto under pressure, the body portion of the liquid divider receiving unidirectional high pressure fluid and acting both as a multiple outlet hydraulic pumping means and as a flow reverser to each circuit connecting therefrom for supplying each reversible liquid dispensing circuit with dispensing fluid under pressure, dispensing first through the feeders of one circuit and then through the feeders of another circuit and so on in successive or step-by-step relation.

Another object of this invention is the provision of a plurality of dispensing circuits connected to and forming part of a liquid dividing means, wherein any one or more of the circuits may have the dispensing feeders removed therefrom and the pipe line connected to form a continuous line, without interfering with the operation of the device or the other circuits, other than in speeding up the time of operation of the other circuit or circuits.

A further object of my invention is to provide an improved device for dividing and distributing fluids comprising a body member having a pair of guide cylinders therein, a reciprocating piston rod in each cylinder, a pair of pistons on each rod adjacent the outer ends thereof, a pair of piston valves on each rod near the mid-portion thereof, said inner piston valves being spaced apart and also spaced from the pistons to provide fluid receiving spaces therebetween, an inlet port in said body connecting into the space between two of said piston valves for receiving high pressure fluid therein, a plurality of outlet ports in said body, suitable ports and inter-connecting conduits connecting from and between the cylinders in such

5 a manner as to cause said piston assemblies to reciprocate continuously in response to fluid injected under pressure into said inlet port and to deliver successively from the outlet ports divided quantities of the fluid, the device also being provided with two exhaust ports connecting through the side walls of each cylinder and connecting the spaces between the piston valves and the pistons of each piston assembly with the corresponding spaces in the other piston assembly in all movable positions of both piston assemblies.

These and other objects auxiliary thereto will appear from the following description of my invention and more particularly pointed out in the 15 appended claims, reference being had to the drawings, in which:

Figure 1 is a schematic view of my new and improved liquid dividing and dispensing system, showing the main body portion of the liquid divider in section;

Figure 2 is a similar sectional view of the main body portion of the liquid divider showing the upper piston rod at the extreme right position and the lower one in its extreme left position;

Figure 3 is a similar sectional view showing both piston rods at their extreme right position; and

Figure 4 is a similar sectional view showing the upper piston assembly at its extreme left position and the lower piston assembly at its extreme right position.

In the drawings, the numeral 1 represents the main body portion of the liquid divider which is suitably bored to form cylindrical apertures 3 and 5, respectively, the ends of which are closed with plugs 7 and 9. The feeder is provided with an inlet port 11 opening into the central portion of the cylindrical aperture 5. The cylindrical apertures 3 and 5 are for convenience termed 35 "cylinders" throughout.

Each cylinder is provided with a piston assembly comprising a piston rod having four spaced heads, the outer two of which act as pistons and the inner two of which act as piston valves, the 45 piston rod in cylinder 3 being designated by the numeral 13 and the piston rod in cylinder 5 being designated by the numeral 15.

Preferably the central portion of the piston rod 13 has an enlarged hub 17 with grooves 19 and 21 on either side, all for a purpose hereinafter to be designated. Next to the grooves 19 and 21 are the piston valves 23 and 25. Located near the ends of piston rod 13 are the pistons 27 and 29 which fit in the end pump chambers respectively of cylinder 3.

Similarly, piston rod 15 has an enlarged hub 31 with grooves 33 and 35 on either side. Next to the grooves 33 and 35 are the piston valves 37 and 39. Located near the ends of piston rod 15 are the pistons or pump plungers 41 and 43 which fit in the end pump chambers respectively of cylinder 5.

Cylinder 3 is provided with dual service or end ports 45 and 47 respectively at each end thereof and cylinder 5 is similarly provided with dual service or end ports 49 and 51.

The ends of both piston rods 13 and 15 project beyond the pistons or pump plungers so as to prevent the closing of the dual service ports. Any other suitable abutment may be provided for permitting flow of fluid into the end chamber when the associated piston is at the outer end of its stroke.

A central passage 53 connects the central portions of cylinders 3 and 5. In this passage I preferably locate control means cooperating with the hub and grooved portions of the two piston assemblies to prevent simultaneous movement of said rods. It is evident that the hubs 17 and 19 could be located elsewhere and a separate passage could be provided for the means for preventing simultaneous movement of the piston rods, but for economy and compactness I prefer to locate them as shown.

It has been the practice to provide a pin to act as a stop member and to prevent simultaneous movement of two such valves, but it has been found that great wear takes place on the contacting heads of said pin type of stop member. I have therefore provided two balls 55 and 57 for contacts, using a small spacer 59 between them, the overall length of the balls and spacer being greater than that of the passage 53 in which they are adapted to operate. The balls give a rolling contact and assure longer life to the device. The diameter of each of the balls 55 and 57 as well as that of the spacers 59, in this embodiment, is less than that of the passage 53, as fluid must be able to pass through the passage 53 at all times that the device is in operation. The control balls and spacer are actuated by the movement of the pistons and are not unduly restrained by gravity.

It is evident that the balls and spacer act as the pin previously acted in conjunction with the hubs 17 and 31 and the adjacent grooves of the respective piston rods in forming a control mechanism which prevents the piston rods from moving at the same time, thereby avoiding failure of operation which might otherwise result if the fluid pressure should be discontinued while the piston rods were passing dead center or if they got in that position when the device was not in operation as by action of gravity or vibration for example.

Adjacent the central portion of each cylinder, two additional dual service ports are also provided in each cylinder, 69 and 79 in cylinder 5 and 89 and 99 in cylinder 3. It will be noticed that said ports are located in such spaced relation that the piston valves on each side of each associated piston hub are adapted to establish conductive connection between one or the other of said end dual service ports in either cylinder and one or the other of the centrally located dual service ports in the other cylinder. For this reason, these four dual service ports 69, 79, 89 and 99 are also called control ports. This arrangement of the ports and piston valves in the lower cylinder 5 serves to pass fluid from

the inlet port 11 to the left hand one 79 of said dual service ports while blocking the other dual service port 69 when the piston assembly is in its extreme left position, and to the right hand dual service port 69 while blocking the other dual service port 79 when the piston assembly is in its extreme right position. It is thought that the action of ports 89 and 99 can similarly be traced.

Circuit pipe line 61 connects dual service or end port 45 (located at the right of cylinder 3) with dual service port 69 (located near and to the right of inlet port 11 in cylinder 5). Circuit pipe line 71 connects dual service or end port 47 (located at the left of cylinder 3) with dual service port 79 (located near and to the left of inlet port 11 in cylinder 5). Circuit pipe line 81 connects dual service or end port 49 (located at the right of cylinder 5) with dual service port 89 (located near and to the left of the opening of passage 53 into cylinder 3). Circuit pipe line 91 connects dual service or end port 51 (located at the left of cylinder 5) with dual service port 99 (located near and to the right of the opening of passage 53 into cylinder 3).

Each of the pipe lines which interconnect between the dual service ports of the device also may have connected therein a reversible feeder of the nature shown in the U. S. Patent Number 1,997,406 issued to David R. Hillis on April 9, 1935, or any number thereof in series. Also only such lines as it may be desired to use for dispensing liquid may be provided with reversible feeders.

I have shown each line as having a series of two feeders; the line 61 having feeders 63 and 67 each having a discharge pipe line 65 connected thereto; the line 71 having feeders 73 and 77 each having a discharge pipe line 75 leading therefrom; the line 81 having feeders 83 and 87 each having a discharge pipe line 85 leading therefrom; the line 91 having feeders 93 and 97 each having a discharge pipe line 95 leading therefrom.

Two exhaust passages 101 and 103, lead from cylinder 3, being so spaced that, when piston rod 13 is at its extreme left position, dual service port 99 may communicate with exhaust passage 103, fluid flowing through said port 99 from pipe line 91 may then pass around the reduced portion of piston rod 13 between piston valves 23 and 27 and pass out of the exhaust port 103. Similarly when piston rod 13 is at its extreme right position, fluid coming into cylinder 3 from pipe line 81, through dual service port 89, will pass around reduced portion of piston rod 13, between piston valves 25 and 29, and thence pass out of the exhaust port 101.

Similarly spaced exhaust passages 101a and 103a also lead from cylinder 5 to cylinder 3 for exhausting fluid that returns through pipe lines 71 and 61 respectively to cylinder 5, said fluid being passed to the respective exhaust portions of cylinder 3 and its respective exhaust ports 101 and 103 which are connected to piping 105 leading to a reservoir or the pump sump.

On the right hand end of piston rod 15 I have provided an indicator rod 109 which extends through the nut 9, the nut being provided with the usual packing. Of course a plurality of indicator rods could be provided, but as long as the workman in attendance sees one indicator move, he knows that the device is still operating satisfactorily.

Operation

A source of fluid under pressure is connected to the inlet port 11. For instance, a pump may be connected directly or by a pipe line 111 to the inlet port 11. Well-known relief valves are used for exhausting air and filling the system. Hence let us assume the system is filled with grease for lubricating bearings connected to the discharge pipes leading from the respective feeders and assume that the parts are in the positions shown in Fig. 1.

Grease will then pass around hub 31 in cylinder 5 and out of dual service port 79 into pipe circuit 71, discharge a measured quantity of grease from feeder 77, out of discharge pipe 75, then by-pass and through the continuation of pipe line 71 leading to feeder 73, discharge a measured quantity of grease from feeder 73 and pass on through the remainder of pipe line 71, through dual service port 47 and into the left hand side of cylinder 3, causing piston rod 13 to shift to the right.

It should be noted that while the passage 53 is open at all times, grease will not pass therethrough while the above operation is taking place as the passage 53 and the portion of cylinder 3 between piston valves 23 and 25 and the dual service port 89 and pipe line 81 with its feeders 87 and 83 have just previously functioned to shift piston assembly 15 to the left, and inlet pressure is now holding the same in its extreme left position.

When the grease has completed its circuit through pipe line 71 from dual service port 79 to dual service port 47, it then shifts piston rod 13 to the right, forcing the balls 55 and 57 and the spacer 59 downwardly in passage 53, so that ball 57 will rest in groove 33, as shown in Fig. 2, thus preventing piston rod 15 from moving simultaneously therewith, as its fluid holding pressure is now relieved.

The grease in the right hand chamber of cylinder 3 is now discharged as by the pumping action of plunger 27. It then passes through dual service port 45 into pipe line 61, operates feeders 63 and 67 and enters cylinder 5 through dual service port 69, passing around reduced portion of piston rod 15, between piston valve 31 and piston 41, from whence it is free to exhaust through passage 103a into cylinder 3, between piston valve 23 and piston 27, which always are in position to open to exhaust passage 103, thence through pipe line 105 to the reservoir or sump of a pump.

Piston rod 13 is now held in its right hand position, as shown in Fig. 2, by the pressure of the grease entering the inlet port. This presses the grease in line 71 against the piston 29 of piston rod 13 until the pressure later is relieved by movement of piston rod 15 to the right, at which time ball 55 will be forced into groove 21 to hold piston rod 15.

After piston rod 13 has moved to the right, as seen in Fig. 2, grease will then pass from the inlet port through passage 53 and around hub 17 in cylinder 3 and out thereof through dual service port 99, into pipe line 91, operate feeders 97 and 93 and pass through dual service port 51 into the left end chamber of cylinder 5, forcing piston rod 15 to the right, which action forces the balls and spacer up to the position shown in Fig. 3.

The movement of piston rod 15 to the right also causes piston 41 to discharge the grease from the right hand chamber of cylinder 5, 75

through dual service port 49, pipe line 81, operating feeders 83 and 81, and the balance of said discharged grease, beyond that of the capacity of feeders 83 and 81, displaces a like quantity of grease in the line, causing it to reenter cylinder 3 through dual service port 89 and to discharge into the exhaust, through exhaust port 101, a like amount.

After both pistons have arrived at the right, as shown in Fig. 3, grease now flows from inlet port 11 into cylinder 5, around hub 31 and out dual service port 69 into pipe line 61, operating feeders 67 and 63 and entering into the right hand end of cylinder 3, through dual service port 45, forcing piston rod 13 to the left. This action forces the balls down as shown in Fig. 4 and also displaces the grease in the chamber at the left end of cylinder 3, causing flow of grease out of dual service port 47, through pipe line 71, operating feeders 73 and 77 and into cylinder 5, through dual service port 79 which then registers with that portion of piston rod 15 between piston valve 39 and piston 43 that registers with exhaust passage 101a—hence it may exhaust through passage 101a and through cylinder 3 between piston valve 25 and piston 29 and exhaust port 101 and exhaust pipe line 105.

Grease now passes from inlet port 11 through the central portion of cylinder 5 and passage 53 into central portion of cylinder 3, around hub 17 and out of dual service port 89 into pipe line 81, operating feeders 87 and 83 and passing through dual service port 49 into the right hand chamber of cylinder 5, forcing piston rod 15 to the left. This forces the balls to the position shown in Fig. 1 and displaces the grease in the chamber at the left of cylinder 5, causing flow of grease in pipe line 91, operating feeders 93 and 97 and passing through dual service port 99 into cylinder 3 between piston valve 23 and piston 27 from whence it is free to exhaust through exhaust port 103.

Care should be taken to see that the capacity of the total number of feeders connected to any one line is less than the capacity of the chamber at the end of any cylinder which discharges through the line.

Aside from the specific embodiment of the invention herein shown and described, it will be understood that numerous details of the construction may be altered or omitted without departing from the spirit and scope of the invention as disclosed and claimed, and that I do not desire to limit the invention to the exact construction herein set forth.

I claim:

1. A dispensing system comprising a plurality of conduits, each conduit being provided with a reversibly operated dispensing and by-passing feeder, a body having a plurality of dual service ports, each end of each of said conduits being connected to a different one of said dual service ports in the body so that each conduit forms a circuit leading from and returning to said body, an inlet port in said body adapted to receive fluid under pressure, exhaust port means in said body, fluid flow conducting passages in said body conductively connecting between said inlet port, dual service ports and said exhaust port means, and two movable members in said body operable by said fluid under pressure in said inlet port in cooperation with each other and with said passages and ports to reverse the direction of flow of fluid in said conduits in time sequence relation.

2. A dispensing system comprising, a plurality of conduits, each conduit being provided with a dispensing and by-passing feeder, a body having a plurality of dual service ports, each end of each of said conduits being connected to a different one of said dual service ports so that each conduit forms a circuit leading from and returning to said body, an inlet port in said body adapted to receive fluid under pressure, exhaust ports in said body, fluid flow conducting passages in said body conductively connecting between said inlet port, said dual service ports, and said exhaust ports, and movable means in said body for directing fluid through each of said conduits in time sequence relation, said movable means being operable by said fluid under pressure and adapted, in cooperation with said passages and ports, to reverse the direction of flow of fluid in said conduits.

3. A dispensing system comprising, a plurality of conduits, each conduit being provided with a dispensing and by-passing feeder, a body having a pair of cylinders, a plurality of dual service ports in said body, half of them opening into and leading from each cylinder, each end of each of said conduits being connected to a different one of said dual service ports so that each conduit forms a circuit leading from and returning to said body, an inlet port in said body opening into the central portion of each cylinder adapted to receive fluid under pressure, piston assemblies in each of said cylinders operable by said fluid under pressure in passing through the system for controlling and reversing the direction of flow of fluid in said conduits in time sequence relation, and exhaust outlets for exhausting returned fluid which has not been dispensed.

4. In combination in a system for dividing and distributing fluids, a body having a pair of cylinders closed at the ends, a reciprocating piston assembly slidably disposed in each cylinder including a piston rod and two pistons near the outer end and two spaced piston valves near the middle portion of said rod, said pistons and piston valves fitting the cylinders in fluid retaining relation and spaced apart by portions of smaller diameter of said rod, providing fluid receiving and passing spaces between, one of said fluid receiving spaces being disposed at the central portion of each piston assembly, each said piston assembly having two outer spaces, a central passage in the body connecting between said central spaces, an inlet port in said body opening into the central space of one of the piston assemblies and connecting to the central space of the other piston assembly for admitting high pressure fluid therein, each cylinder having an end port adjacent each end for applying fluid pressure on the end of the adjacent piston for moving the piston assembly to the other end of the cylinder, four control ports, two in each cylinder spaced on each side of the center thereof, said ports being opened and closed by the movements of the piston assemblies and so arranged that each assembly controls the application of fluid pressures selectively on the ends of the other piston assembly to move both piston assemblies to and fro as long as fluid pressure is applied into said inlet ports, two exhaust port passages opening through the side walls of each cylinder at points on opposite sides of the center and sufficiently spaced toward the ends of the cylinders from said control ports to avoid being connected with the central space of the piston assembly in either position thereof and to connect with the

outer space of each assembly when it is moved toward the center of the cylinders, four control conduit lines, one connecting from each control port and extending externally of said body and returning to said body connected into one of said end ports for applying actuating fluid pressures therein, and a fluid measuring, dispensing and by-passing feeder disposed in one or more of said control lines for operation to measure and dispense a portion of the control fluid received from its line and adapted to by-pass additional fluid to the continuation of its line.

5. In combination in a system for dividing and distributing fluids, a body having a pair of cylinders closed at the ends, a reciprocating piston assembly slidably disposed in each cylinder, each piston assembly including a rod and two piston valves spaced on opposite sides of and adjacent the center and two pistons spaced adjacent the opposite ends, said pistons and piston valves fitting the cylinders in fluid retaining relation and being spaced apart for providing fluid receiving and passing spaces between, one of said fluid receiving spaces being disposed at the central portion of each piston assembly, a central passage connecting between said central spaces, two exhaust ports connecting through the side walls of each cylinder and suitably positioned for connecting the space between the piston valve and the piston at each end of each piston assembly with the corresponding space in the other piston assembly in all movable positions of both piston assemblies, an inlet port in said body opening into the central space of one of the piston assemblies for admitting high pressure fluid therein, each cylinder having an end port adjacent each end for applying fluid pressure on the end of the adjacent piston for moving the piston assembly to the other end of the cylinder, control ports opened and closed by the movements of the piston assemblies and so arranged that each assembly controls the application of fluid pressures selectively on the ends of the other piston assembly to move both piston assemblies to and fro as long as fluid pressure is applied into said inlet ports, control conduit lines connecting one from each control port and extending externally of said body and returning to said body connected into one of said end ports for applying actuating fluid pressures therein, and a fluid dispensing feeder disposed in one or more of said control lines for operation to dispense a portion of the control fluid which is passed through said control conduit line for actuating said piston assemblies.

6. In combination in a system for dividing and distributing fluids, a body having a pair of guide cylinders therein, a reciprocating piston rod in each cylinder, a pair of pistons on each rod adjacent the outer ends thereof, a pair of piston valves on each rod near the mid-portion thereof, said piston valves being spaced apart and also spaced from the pistons to provide fluid receiving spaces therebetween, an inlet port in said body connecting into the space between two of said piston valves in one cylinder and connecting into the corresponding space in the other cylinder for receiving high pressure fluid therein, exhaust passages in said body opening one from each space between each piston valve and each piston of each cylinder, dual service ports suitably positioned in said cylinder and interconnecting control conduits connecting from and between the dual service ports of said cylinders to cause said piston assemblies to reciprocate continuously in response to fluid injected under pres-

sure into said inlet port and to deliver successive-
ly from the outlet ports divided quantities of the
fluid in reversing flow relation in said conduits,
said control conduits extending externally of said
body, and a fluid dispensing feeder device dis-
posed in one or more of said control lines for op-
eration to dispense a portion of the control fluid
passing therethrough.

7. In combination in a system for dividing and
distributing fluids, a body having a pair of cyl-
inders closed at the ends, a reciprocating piston
assembly slidably disposed in each cylinder, each
piston assembly including a piston rod having two
piston valves near the mid-portion thereof and
two pistons, one adjacent each end thereof, said
valves and pistons fitting the cylinders in fluid
retaining relation and said valves being spaced
apart and also spaced from the pistons to pro-
vide fluid receiving and passing spaces therebe-
tween, one of said fluid receiving spaces being
disposed at the central portion of each piston
assembly, a central passage connecting between
said central spaces, control means in said central
passage actuatable by either piston assembly
moving from an extreme position to secure the
other piston assembly in an extreme position un-
til the other has reached an extreme position,
an inlet port in said body opening into the cen-
tral space of one of the piston assemblies for
admitting high pressure fluid therein, each cyl-
inder having an end port adjacent each end for
applying fluid pressure on the end of the ad-
jacent piston for moving the piston assembly to
the other end of the cylinder, four control ports
opened and closed by the movements of the pistons
and so arranged that each assembly
controls the application of fluid pressures se-
lectively on the ends of the other piston assembly
to move both piston assemblies to and fro as
long as fluid pressure is applied into said inlet
port, four control conduit lines connecting one
from each control port and extending externally
of said body and returning to said body connect-
ed into one of said end ports for applying actuating
fluid pressures therein, a reversibly oper-
able fluid dispensing feeder disposed in one or
more of said control lines for operation to dis-
pense a portion of the control fluid passed there-
through, exhaust ports in said body opening from
the fluid receiving spaces between the piston
valves and the pistons, spaced apart on oppo-
site sides of the center of each piston assembly,
and fluid conducting lines connecting from re-
spective ones of said exhaust ports adapted for
returning some of the distributing fluid to a res-
ervoir or sump of a pump.

8. An apparatus for dividing and distributing
fluids comprising, a body having two cylinders
closed at the ends, a piston assembly slidably dis-
posed in each cylinder, each piston assembly in-
cluding two piston valves and two pistons slid-
ing in fluid retaining relation in the cylinder
and rigidly spaced apart with the two piston
valves on each side of the center of the assem-
bly providing fluid receiving spaces between said
piston valves and the pistons being spaced out-
wardly therefrom and providing intervening
spaces, each cylinder having a dual service end
port adjacent each end for receiving fluid under
pressure to apply on the adjacent end of the ad-
jacent piston for moving the piston assembly to
the other end of the cylinder and for discharg-
ing fluid therefrom when pressure is applied on
the other end of the piston assembly, additional
dual service ports, one complementary to and

cooperating with each of said end ports and
opening through an intermediate portion of the
other cylinder side wall for control by an inner
piston valve of the piston assembly therein, four
5 conduits, one connecting each dual service end
port to its complementary dual service control
port, a reversibly operable and by-passing feed-
er connected to each conduit, an inlet port in
said body opening into each cylinder at the cen-
tral space of each of the piston assemblies, two
10 exhaust passages connecting between the two
cylinders and opening into the spaces between
the valve pistons and the pistons of each assem-
bly, and exhaust passages connecting and open-
15 ing therefrom for exhausting undistributed fluid
returning to the apparatus.

9. Apparatus for distributing fluids comprising
a body member having a pair of cylinders
therein, a reciprocating piston rod in each cylin-
20 der, a pair of pistons on each rod adjacent the
outer ends thereof, a pair of piston valves on
each rod near the mid-portion thereof, said pis-
ton valves being spaced apart and also spaced
from the pistons to provide fluid receiving spaces
25 therebetween, an inlet port in said body connect-
ing into each cylinder at the space between
two of said piston valves for receiving high pres-
sure fluid therein, ports suitably positioned in
30 said cylinders in cooperative relation to said pis-
tons and piston valves, interconnecting conduits
connecting from and between the ports in said
cylinders to cause said piston assemblies to re-
ciprocate continuously in response to fluid in-
35 jected under pressure into said inlet port, one
of said conduits being adapted for connection
to a reversibly operable dispensing and by-pass-
ing feeder, two spaced exhaust passages connect-
ing through the body between the spaces be-
40 tween each adjacent piston valve and piston,
and exhaust passages connecting and opening
therefrom.

10. Apparatus for distributing fluids including
the combination set forth in claim number 6 and
also having means for preventing movement of
45 both piston rods at the same time.

11. A fluid dispensing system comprising, a
body having a cylinder therein, four dual service
ports in said body opening into said cylinder at
axially spaced points, one at each end thereof
50 and one on each side of the center thereof, an-
other cylinder in said body, four dual service
ports in said body opening similarly into said
second mentioned cylinder and corresponding in
position to the ports opening into the first cylin-
55 der, four conduits, each conduit connecting from
one of the dual service end ports of one cylinder
to one of the dual service ports in the mid-portion
of the other cylinder, an inlet port in said body
opening into said cylinders to receive fluid under
60 pressure therein, piston assemblies in each of
said cylinders operable by the fluid under pres-
sure in passing through the system for reversing
the direction of flow of fluid in said conduits,
exhaust ports opening from the cylinders for ex-
65 hausting some of the returned fluid, a fluid dis-
pensing and by-passing feeder disposed in at
least one of said conduits for operation by the
fluid passing reversely therethrough, and ex-
haust passages leading from said exhaust ports
70 for exhausting undispensed fluid returning to
said cylinders from said conduits.

12. A fluid distributing system comprising, a
body, a plurality of cylinders in said body, a plu-
rality of ports opening into each of said cylinders
at corresponding similar points, some being ad-

adjacent the ends thereof and others being spaced intermediate the ends of the cylinders, conduits connecting the ends of each cylinder into another cylinder, an inlet port in said body for receiving fluid under pressure therein, conduit means connecting each cylinder to the inlet port for the flow of fluid through all the cylinders, a piston assembly in each cylinder arranged to be automatically shifted back and forth between two extreme positions by the fluid under pressure, each piston assembly having spaced pistons and piston valve means so spaced and positioned relative to said ports as to alternately connect the ends of the cylinders to fluid under pressure and to alternately connect the cylinders at their opposite ends to outlets in other cylinders through said conduit means whereby said piston assemblies continuously reciprocate to discharge fluid from opposite ends thereof so long as fluid under pressure is provided, one or more of said conduit means consisting of a pipe or pipes extending externally of said body, fluid dispensing and by-passing feeders connected into such external pipe or pipes for operation by the fluid passing reversely therethrough, two exhaust passages connecting between the two cylinders and opening into the spaces between the valve pistons and the pistons of each assembly, and exhaust passages connecting and opening therefrom for exhausting undistributed fluid returning to the apparatus.

13. A fluid dispensing system, comprising, a body having a plurality of cylinders therein, eight dual service ports in said body, four of said dual service ports opening into each cylinder, one at each end thereof and one on each side of the center thereof, an inlet port in said body opening into said cylinders to receive fluid under pressure therein, four conduits, each conduit leading from one of the dual service end ports of one cylinder to one of the dual service ports in the mid-portion of the other cylinder, piston assemblies in each of said cylinders operable by the fluid under pressure in passing through the

5 system for reversing the direction of flow of fluid in said conduits, exhaust ports opening from the cylinders for exhausting some of the returned fluid, and a fluid dispensing and by-passing feeder disposed in at least one of said conduits for operation by the fluid passing reversely therethrough.

14. A fluid distributing system comprising, a body, a plurality of cylinders in substantially 10 parallel relation in said body, each end of each cylinder being internally threaded, the ends of the cylinders having threaded members therein, a plurality of ports opening into each of said cylinders at corresponding similar points, some 15 being adjacent the ends thereof and others being spaced intermediate the ends of the cylinders, conduits connecting the ends of each cylinder into another cylinder, an inlet port in said body for receiving fluid under pressure therein, 20 conduit means connecting all the cylinders continuously to the inlet port for the flow of fluid through all the cylinders, a piston assembly in each cylinder arranged to be automatically shifted back and forth by the fluid under pressure, each piston assembly having spaced pistons and intermediate piston valve means so positioned relative to said ports as to alternately connect the 25 ends of the cylinders to fluid under pressure and to alternately connect the cylinders at their opposite ends to outlets in other cylinders through said conduit means whereby said piston assemblies continuously reciprocate to discharge fluid from opposite ends thereof so long as fluid under pressure is provided, some of said conduit means 30 consisting of pipes extending externally of said body, fluid dispensing and by-passing feeders connected into some of the external pipes for operation by the fluid passing reversely therethrough, and exhaust passages connecting between and opening into the two cylinders into the spaces between the valve pistons and the pistons on each piston assembly for exhausting fluid therefrom.
